UNITED STATES PATENT OFFICE

LESLIE JOHN HANCOCK, OF SUTTON, ENGLAND

FLAME CUTTING BURNER APPARATUS

Application filed March 15, 1932, Serial No. 599,021, and in Great Britain December 29, 1931.

This invention relates to flame cutting burner apparatus of the kind comprising a longitudinally traveling carriage and a transversely traveling carriage mounted upon the longitudinally moving one, the said transversely traveling carriage supporting a flame cutting burner or blow-pipe at one end and a tracer device at the other end.

The primary object of the invention is the provision of synchronizing means between the opposite sides of the longitudinally movable carriage for the purpose of preventing relatively independent traveling movements of the said sides, i. e. preventing whip of the apparatus.

A further object of the invention is the provision of a single transverse track rail on the longitudinally traveling carriage on which rail the transversely traveling carriage runs.

The above and other objects of the invention will be clear from the following description taken in conjunction with the accompanying drawings, and the claims.

In these drawings:

Fig. 1 is an end elevation of a flame cutting burner apparatus constructed in accordance with the invention;

Fig. 2 is a plan view of the said apparatus;

Fig. 3 is a side elevation thereof;

Fig. 4 shows a modification of one feature of the invention; and

Fig. 5 is a detail showing a double burner arrangement.

In these drawings the longitudinally movable carriage comprises two tubular rails 1 and 2 extending from side to side of the machine and two side castings 3—3 on which are bosses 4 and 5 for the reception of the ends of the tubular rails, one of the rails, 1, being disposed at the leading ends of the castings and the other, 2, at the following ends. The track of this frame comprises two longitudinal rails 6—6 of right-angular section arranged one at one side of the machine and the other at the other side thereof; and the frame is borne on this track by two wheels 7 and 8 rigidly fixed at the ends of a shaft 9 passing through the tubular rail 1

and supported in bearings at the ends of the rail. The wheel 7 is of the kind provided at each side with flanges which engage the sides of the track rail and so prevent lateral displacement of the roller and carriage.

For the purpose of ensuring that the carriage does not "whip", i. e., does not depart from a true right-angular position with respect to track rails 6—6, the inner sides of the wheels or the ends of the shaft adjacent these sides have fixed to them spur wheels 10—10 whilst racks 11—11 for engagement with these wheels 10 are fixed on the inner sides of the tracks 6—6, one rack to each track. By this means synchronous movement of the wheels 7—8 and true movement of the carriage is ensured. The diameter of the pitch circle of each wheel 10 is equal to the running diameter of its respective wheel (7 or 8).

The transversely movable carriage comprises a casting 12 with two downwardly and sidewardly projecting wings 13—13 for the fixing of the ends of stubs 15—15 for rollers 16—16, and a downwardly extending central part 17 for the fixing of the end of stub 18 for a check roller 19. The rollers 16 have V grooves in their peripheries and engage and run on the upper part of the tubular rail 1, whilst the check roller which is of plain form bears against the under part of the rail 2.

The body 12¹ of the casting 12 is of hollow cylindrical form and receives in the hollow an intermediate part of a tubular arm 20, one projecting end 21 of which is considerably shorter than the other end 22 and has secured to it a bracket 23 which bears the tracer 24, and the end 22 of which receives a telescopic tube 25 carrying at its outer end the burner 26. The arm 20 is adjustably fixed in the part 12¹ by means of a clamping bolt 27 passing through a longitudinal slot 28 in 12¹ and screwing into the arm 20: this arrangement prevents rotation of the tube and enables adjustments of the tracer to be made with respect to the pattern table 29. The bracket 23 is provided with a hollow boss 30 into which the outer end of the part 21 enters and in which this part is remov-

- ably secured by clamping bolts 31. The tracer and the means for mounting it on the bracket 23 are of known kind.
- The tube 25 is adjusted longitudinally of the arm 20, for the purpose of setting the burner in the most convenient position with respect to a workpiece, not shown, borne by a table comprising channel irons 32-32, by means of a pinion 33 meshing with a toothed rack 34 on the upper side of the tube, a bracket 35 rigid with 20 bearing the spindle 36 of the pinion and a hand wheel 37 at one end of the spindle providing means for turning the said pinion and so shifting the tube.
- 10 The burner, which is mounted so as to be capable of limited universal movement to enable bevel cuts to be made, is provided with a hollow boss 38 in which the outer end of 25 is received and is clamped by a bolt 39.
- 15 The base of the machine on which the devices above described are supported comprises castings 40-40 and 41-41 braced together in pairs by bars and joists 42 and secured together, one pair in front of the other, at 43. The castings 40 have sidewardly projecting arms 44 to which the track rails 6-6 and the racks 11-11 are secured by bolts 45 passing through the rails and racks, through spacing washers 46 between the racks, and screwing into the outer ends of the arms.
- 20 The table 29 is reversible one side being for the reception of a templet of strip or other suitable kind and the other side for a drawing. The mounting permitting of reversal of the table comprises trunnions 47 extending inwardly of the upper ends of the castings 40 and entering recesses at the sides of the table 29, said recesses being about centrally of the table. The table is locked in whichever position it is turned to by means of removable pins 48 arranged to take into recesses such as 49 at the opposite ends of the sides of the table.
- 25 In the operation of the machine the tracer follows or is guided along lines of a pattern, templet, drawing or the like on the table 29 and directs the carriages in their respective directions at separate moments or simultaneously so that profiles consisting of longitudinal, transverse and curved and oblique lines are followed out by the burner 26, the paths of the tracer and burner being similar. The side plates 3 have downwardly extending limbs 50 at the ends of which are fitted rollers 51. The rollers bear on the under sides of the track rails 11 and prevent the carriages tilting owing to the weight of the long arm 22, the burner 26 and the parts associated with these, the tilting tendency being transmitted to the rollers through check roller 19 and the check rail 2. Stops 52-52 adjacent the ends of each rail 11 limit the path of travel of the longitudinal carriage.
- 30 In a modification of the invention the arm

25 as shown in Figure 4, may be formed as a substantially U-shaped arm including limbs 25', 25^a and a yoke 25^b, the limb 25^a extending forwardly of the machine beneath the table 29 and terminating in a burner 26^c arranged over a work-table comprising channel irons 32^c. This arrangement considerably reduces the floor space required for the machine.

70 The invention contemplates the use of two burners, illustrated more particularly in Figure 5, wherein the arm 25 through the medium of the joint 53 carries a double-arm bracket 54 terminating at its ends in sockets 55 of conventional type designed for holding the blow pipes.

75 What I claim is:—

1. In flame cutting burner apparatus, longitudinal track rails, toothed racks adjacent the longitudinal rails, and a traveling carriage with track wheels that bear upon the track rails and with toothed wheels that have a rigid connection between them and mesh with the toothed racks for the purpose of preventing relatively independent traveling movements of the track wheels on the track rails.

2. In flame cutting burner apparatus, longitudinal track rails, toothed racks adjacent the longitudinal rails, and a traveling carriage with track wheels that bear upon the track rails, toothed wheels that mesh with the toothed racks, and a transverse shaft rigidly connecting the toothed wheels and the track wheels together for the purpose of preventing relatively independent traveling movements of the track wheels on the track rails.

3. In flame cutting burner apparatus, a longitudinally traveling carriage, track wheels on the carriage and longitudinal track rails on which the said track wheels run, toothed racks adjacent to each longitudinal track rail and toothed wheels on the carriage adjacent to the track wheels, a rigid connection between the toothed wheels and the track wheels for the purpose of preventing relatively independent traveling movements of the track wheels on the track rails, a transversely traveling carriage, a single transverse track on the longitudinally traveling carriage, and track rollers on the transversely traveling carriage which run on the said single transverse track.

4. In flame cutting burner apparatus, a longitudinally traveling carriage, track wheels on the carriage and longitudinal track rails on which the said track wheels run, toothed racks adjacent to each longitudinal track rail and toothed wheels on the carriage adjacent to the track wheels, a rigid connection between the toothed wheels and the track wheels for the purpose of preventing relatively independent traveling movements of the track wheels on the

track rails, a transversely traveling carriage, a single transverse track on the longitudinally traveling carriage, a check rail parallel with the said transverse rail on the carriage, 5 track rollers on the transversely traveling carriage which run on the said single transverse track and a check roller which runs along the said check rail.

5. In flame cutting burner apparatus, a longitudinally traveling carriage comprising side plates, cross rails extending between the side plates, and track wheels on the said side plates, longitudinal track rails on which the said track wheels run, a toothed 10 rack adjacent to each longitudinal track rail and toothed wheels on the carriage adjacent to the track wheels, a rigid connection between the toothed wheels and the track wheels for the purpose of preventing relatively independent traveling movements of the track wheels on the track rails, a transversely traveling carriage, a 15 single transverse track on the longitudinally traveling carriage, track rollers on the transversely traveling carriage which run on the said single transverse track, an arm projecting rearwardly of the said transversely traveling carriage and terminating 20 in a tracer, another arm considerably longer than the other and projecting forwardly of the said carriage, a telescopic member mounted transversely with respect to the said longer arm, and a blow-pipe burner 25 secured to the said member.

6. In flame cutting burner apparatus, a longitudinally traveling carriage comprising side plates, cross rails between the side plates and track wheels and check wheels on 30 the side plates, longitudinal track rails against the upper and lower sides of which the track wheels and check wheels respectively run, toothed racks adjacent to each longitudinal track rail, toothed wheels on the carriage adjacent to the track wheels, a rigid connection between the toothed wheels and the track wheels for preventing relatively independent traveling movements of the track wheels on the longitudinal track rails, a 35 transversely traveling carriage, and track rollers and check rollers on the said transversely traveling carriage, which operate with the track rollers on one of the cross rails of the longitudinally traveling carriage 40 and a check roller against another cross rail thereof.

7. In flame cutting burner apparatus, a longitudinally traveling carriage, track wheels on the carriage and longitudinal 45 track rails on which the said track wheels run, toothed racks adjacent to each longitudinal track rail, toothed wheels on the carriage adjacent to the track wheels and a rigid connection between the toothed wheels 50 and the track wheels for the purpose of preventing independent traveling movements of the track wheels on the track rails, a transversely traveling carriage, a single transverse track on the longitudinally traveling 55 carriage, track rollers on the transversely traveling carriage which run on the said single transverse track, an arm projecting rearwardly of said carriage and terminating in a tracer, and another arm, considerably 60 longer than the other, projecting forwardly 65

of the said carriage and secured at its forward end to a blow-pipe burner.

8. In flame cutting burner apparatus, a longitudinally traveling carriage, track wheels on the carriage and longitudinal 70 track rails on which the said track wheels run, toothed racks adjacent to each longitudinal track rail and toothed wheels on the carriage adjacent to the track wheels, a rigid connection between the toothed wheels and the track wheels for the purpose of preventing relatively independent traveling movements of the track wheels on the track rails, a transversely traveling carriage, a single transverse track on the longitudinally traveling carriage, track rollers on the transversely traveling carriage which run on the said single transverse track, an arm projecting rearwardly of the said transversely traveling carriage and terminating 75 in a tracer, another arm considerably longer than the other and projecting forwardly of the said carriage, a telescopic member mounted transversely with respect to the said longer arm, and a blow-pipe burner 80 secured to the said member.

9. In flame cutting burner apparatus, a longitudinally traveling carriage, track wheels on the carriage and longitudinal 85 track rails on which the said track wheels run, toothed racks adjacent to each longitudinal track rail and toothed wheels on the carriage adjacent to the track wheels, a rigid connection between the toothed wheels and the track wheels for the purpose of preventing relatively independent traveling movements of the track wheels on the track rails, a transversely traveling carriage, a single transverse track on the longitudinally traveling carriage, track rollers on the transversely traveling carriage which run on the said single transverse track, an arm projecting rearwardly of the said transversely traveling carriage and terminating 90 in a tracer, another arm considerably longer than the other and projecting forwardly of the said carriage, a telescopic member mounted transversely with respect to the said longer arm, and a blow-pipe burner 95 secured to the said member.

10. In flame cutting burner apparatus, a longitudinally traveling carriage, track wheels on the carriage and longitudinal 100 track rails on which the said track wheels run, toothed racks adjacent to each longitudinal track rail, toothed wheels on the carriage adjacent to the track wheels and a rigid connection between the toothed wheels and the track wheels for the purpose of preventing relatively independent traveling movements of the track wheels on the track rails, a transversely traveling carriage, a single transverse track on the longitudinally traveling carriage, track rollers on the transversely traveling carriage which run on the said single transverse track, an arm projecting rearwardly of the said transversely traveling carriage and terminating 105 in a tracer, another arm considerably longer than the other and projecting forwardly of the said carriage, a telescopic member mounted transversely with respect to the said longer arm, and a blow-pipe burner 110 secured to the said member.

11. In flame cutting burner apparatus, longitudinal track rails, toothed racks adjacent to the longitudinal rails, a traveling carriage with track wheels that bear upon the track rails and with toothed wheels that have a rigid connection between them and mesh with the toothed racks for the purpose of preventing relatively independent traveling movements of the track wheels on the track rails, a transversely traveling carriage and transverse track for this carriage on the longitudinally traveling carriage, a tracer 115

element and a burner carried fore and aft of the transversely traveling carriage, a pattern table beneath the tracer element, a mounting permitting of reversal of the said table, and locking means for retaining the table in horizontal position.

11. In flame cutting burner apparatus, longitudinal track rails, a traveling carriage, track wheels on the carriage for cooperation with said track rails, and cooperating means controlled and operated by the track wheels for maintaining a true right angular position of the carriage relative to the track rails during movement of the carriage.

12. In flame cutting burner apparatus, a frame, longitudinal track rails carried thereby, a traveling carriage, track wheels on the carriage for cooperation with said rails, and cooperating members on the carriage and frame for maintaining the carriage in true right angular position with respect to the track rails during movement of the carriage, one of said cooperating members being operated by the track wheels.

13. In flame cutting burner apparatus, a frame, longitudinal track rails carried by the frame, a movable carriage, track wheels carried by the carriage and cooperating with the rails, and a rack and pinion cooperation between the carriage and frame during movement of the carriage, said cooperation being controlled by and in the movement of the track wheels.

14. In testimony whereof I affix my signature.

LESLIE JOHN HANCOCK.
